Richard Bemish,
By E.B. Whitmore, Atty.

UNITED STATES PATENT OFFICE.

RICHARD BEMISH, OF ROCHESTER, NEW YORK.

FIRE-ESCAPE.

SPECIFICATION forming part of Letters Patent No. 369,681, dated September 13, 1887.

Application filed May 20, 1887. Serial No. 238,814. (No model.)

To all whom it may concern:

Be it known that I, RICHARD BEMISH, of Rochester, in the county of Monroe and State of New York, have invented a new and useful Improvement in Fire-Escapes, which improvement is fully set forth in the following specification and shown in the accompanying drawings.

The object of my invention is to produce an improved fire-escape, the same being essentially a flexible ladder held in an inclosure placed over a window within the room, said ladder to be lowered out of the window from the inclosure to the ground.

15 The novelty of the device consists, mainly, in the form of the inclosure, the manner of holding the ladder within the same, and the manner of opening said inclosure at the time of need to present the ladder for use as a 20 means of escape. The invention is hereinafter fully described, and the novel features thereof particularly pointed out in the claims.

Referring to the drawings, Figure 1 is a front elevation of the box or inclosure containing the ladder with parts of the casing of the window, said inclosure being open and in part vertically sectioned, as on the dotted line *x* in Fig. 2, and one position of the ladder being shown in dotted lines. Fig. 2 is a side elevation of the same, seen as indicated by arrow in Fig. 1, the wall of the building, window-casing, and a part of the inclosure being vertically sectioned, as on the dotted line *z* in Fig. 1, parts being shown in two positions by full and dotted lines. Fig. 3, drawn to a larger scale, is a side elevation of some of the lower parts of the inclosure with associated parts, seen in the direction in which Fig. 2 is seen, parts being shown in various positions by full and dotted lines. Fig. 4, drawn to a small scale, shows the relation of the escape to the wall and windows of the building, the parts being seen in the direction in which Fig. 2 is seen, the wall being vertically sectioned 45 through a tier of windows, as on the dotted line *x'* in Fig. 1. Fig. 5 is a view of a window as seen from within the room, drawn to more fully show the manner of placing the fire-escape against the casing and the position of the ladder when lowered. Fig. 6, drawn to the scale to which Figs. 3 and 7 are drawn and

viewed from the same direction, shows the fastening device for the door of the inclosure and the manner of operating the same, the parts of the door and front wall of the inclosure shown being vertically sectioned, as on the dotted line *y'* in Fig. 1, parts being shown in two positions by full and dotted lines. Fig. 7, seen in the direction in which Fig. 3 is seen, shows the supports for the door, a part of the latter and the side wall of the inclosure being vertically sectioned, as on the dotted line *z'* in Fig. 1.

Referring to the parts, A is a portion of the outer wall of a building, and B the windows in 65 said wall.

C is the inclosure or holder for the ladder D, which latter is flexible and ordinarily wound upon a reel, E, held within the said inclosure. The inclosure is secured rigidly by 70 bolts *a* to the wall of the building, over the window, which inclosure may be made ornamental and to form a part of the casing of the window, as shown in Fig. 5. The inclosure is formed with a door, F, joined thereto by ordinary hinges, *b*, so as to turn or swing downward. The door is composed of a part, *c*, of the front wall of the inclosure and a part, *d*, of the under wall thereof, said parts *c* and *d* being joined by ordinary hinges, *e*. When the 80 door is closed, all of the parts of the device are inclosed and out of sight.

The door is provided with a fastener, G, consisting of a rigid catch, *f*, co-operating with a tilting latch, *g*, held upon a pivot, *h*, projecting inwardly from a side wall of the inclosure. The latch may be operated by a weighted part, *i*, or a simple spring, as thought desirable.

k is a rigid stop-pin, to prevent the latch being turned too far by said weight or spring.

From this description of the parts it will be understood that when the door is swung upward to place it will be held by the latch in a manner such that it cannot be opened by a person occupying the room. This is to prevent the ladder being used by any person for improper purposes.

It is designed to place one of these fire-escape devices over an available window or outside 100 door of each room of the building above the first story, and operate the fastener G, to re-

lease the door of each, by means of an electro-magnet, *l*, placed to act upon the latch *g*, simple closers for the circuit being placed at different points in the building, as judgment may dictate; or the respective latches may be operated by simple pull-wires *n*, joined by bell-cranks *o*. These methods of operating the latches are suggested as being convenient, but no novelty is here claimed for them.

10 The part *d* of the door is provided with a rigid hook, *p*, to which the lower end of the inclosed ladder is attached, as shown. This hook is turned so as to open out in a direction away from the hinge-joint at *b*, or so that

15 when the door is turned downward said hook will open downward. A spring, *r*, secured rigidly to the back wall, *s*, of the inclosure, is held to bear against the door, to throw it down with force when released from the fastener *G*,

20 for the purpose of drawing a portion of the ladder from the reel. The ladder, being attached to the hook *p*, is pulled downward by the weight of the falling door, assisted by the spring, so that said ladder will hang in front

25 of the window, as shown in Figs. 1, 3, and 4, in convenient reach of the occupant of the room. The person wishing to use the ladder seizes the pendent end thereof, and, pulling it downward, unreels the whole ladder, which

30 remains attached to the reel and reaches to the ground, it being directed out of the window. The ladder is rewound upon the reel by means of an ordinary crank applied to the squared head *a'* of the shaft of the reel.

35 To further support the door, I supply it with two rigid dowel pins or supports, *u*, in position to enter respective opposing cavities *v* in the side walls of the inclosure. These pins, having bearings at the lower sides of said cavities, hold the weight of the door, while the fastening device *G* holds the door closed, as above stated. Two of the fasteners *G* may be

employed, if thought desirable—one at each side of the inclosure.

The ladder may be formed of chains having 45 links flat or curved, with hollow rungs, or the sides of the ladder may be made of cable. No novelty is claimed for the ladder as such.

An electric bell, *b'*, is supplied to the inclosure, to sound when the magnet is brought into 50 action to unfasten the door, to awaken the occupant of the room. This alarm-bell is of common kind as to form and operation.

The hook *p*, opening downward, allows the end of the ladder to slip off and hang only from 55 the reel when the door is thrown down. This will be readily understood from viewing Fig. 3.

What I claim as my invention is—

1. In combination with a flexible ladder, an inclosure therefor having a part, *c*, of its front wall joined to a part, *d*, of its under wall by hinges, said part *d* being connected by hinges to the remainder of said under wall, a catch or holder for said part *c*, dowel-pins rigid with said part *c*, and openings *v* in the side 65 walls of said inclosure for said dowel-pins, of larger diameter than the diameter of said dowel-pins, and in position to have said pins bear upon the under sides of said respective openings when the door is closed, substantially 70 as shown and described.

2. In combination with a flexible ladder, an inclosure therefor, said inclosure having a part, *c*, of its front wall joined to a part, *d*, of its under wall by a hinge-joint, said part *d* being 75 connected by a hinge-joint to the remainder of said under wall, a fastener for said part *c*, and supports rigid with said part *c*, held to engage the side walls of said inclosure, substantially as and for the purpose specified.

RICHARD BEMISH.
